BRACKET

Tamino W. Tregear, Seattle, Wash.

Application June 13, 1947, Serial No. 754,326

1 Claim. (Cl. 248—200)

1

This invention relates to those devices known, in a general way, as "brackets" and it has reference more particularly to a bracket assembly, comprising an attaching or supporting plate and a bracket arm that is extended from the plate for the support or suspension of an article therefrom.

It is the principal object of this invention to provide an attractive and serviceable bracket of the kind above-stated, characterized by the fact that the supporting plate and arm may be arranged in various relationships to adapt the device for attachment to or mounting on window rails, walls, casings, chair-rails or other means of support.

It is also an object of the invention to provide a bracket that is relatively inexpensive; easy to apply and use and which permits the ready removal of the bracket arm from the affixing plate when such is found desirable.

Still further objects of the invention reside in the details of construction of the associated parts and in their relationship and mode of use as will hereinafter be fully described.

In accomplishing these and other objects of the invention, I have provided the improved details of construction, the preferred forms of which are illustrated in the accompanying drawings, wherein—

Fig. 1 is a perspective view of a bracket embodied by the present invention, showing it as applied to a window rail and illustrating its use for the suspending of a flower basket therefrom.

Fig. 2 is a front view of the bracket as applied in Fig. 1.

Fig. 3 is a cross-section taken on line 3—3 in Fig. 2, particularly showing the relationship of the bracket parts and window rail.

Fig. 4 is a perspective view illustrating another relationship of the bracket arm, the attaching plate, and support.

Fig. 5 illustrates the method of applying the attaching plate to a window casing or the like.

Fig. 6 is a perspective view of an attaching plate of an alternative form.

Fig. 7 is a perspective view of an attaching plate of still another form.

Referring more in detail to the drawings—

In its present preferred form of construction, the bracket assembly comprises an attaching plate that is designated in its entirety by reference numeral 10 and a bracket arm designated in its entirety by reference numeral 12.

The attaching plate comprises a single piece of sheet metal of suitable kind, originally of rec-

tangular form, that is bent to angular form to provide a flange 13 across one end that extends in a plane at a right angle to the body portion of the plate designated by numeral 14. Formed in the flange 13, are holes 15 for the passing therethrough of brads or tacks to aid in securing the plate in position as presently explained. Formed in the body portion 14 of the plate, parallel with and close to its lower edge, as seen in Fig. 3, is a slot 16 for the reception of the mounting end portion of the bracket arm 12.

The bracket arm 12 is a flat, rigid strip of metal and may have various forms. As shown best in Fig. 3, its main portion, between its ends, is straight. At its outer end, it is formed into a forwardly and downwardly curved hook portion 17 in which the loop or ball of a flower pot, or the like, 18 may be applied for the suspension of the pot. At its lower end, the bracket arm has a mounting portion 20 that is bent at a substantial angle to the straight or main portion of the bracket, and extends in a direction opposite to the hook portion 17. The mounting portion has an upwardly offset loop or bend 23 formed therein, near the junction of the part 20 with the main portion of the bracket arm. The relationship of the main portion of the bracket arm, the hook portion 16 and the mounting portion 20 thereof, for most uses of the bracket, would be as shown in Fig. 3, but this relationship may be altered for specific uses.

Assuming the parts of the bracket to be so constructed, the mode of application and use of the device would be as follows:

35 In applying the bracket to a window rail as in Fig. 1, the attaching plate would be applied to the rail, designated at 24, in a manner whereby the flange 13 lies flatly upon the top surface of the rail and the body of the plate is disposed flatly against the front surface of the rail. Then, to insure against displacement, tacks or brads, as at 30, are applied through the holes 15 in flange 13 and driven into the rail. Then the mounting end portion 20 of the bracket arm is passed through the slot 16 of the plate and the upwardly formed loop portion 23 is seated in the slot and the end of part 20 is engaged against the underside of the rail, as illustrated in Figs. 1 and 3.

The weight of an article suspended from the outer end hook 17 of the bracket arm as in Fig. 1, effects a clamping action by the parts 10 and 20 against top and bottom sides of the window rail that would, under normal conditions, eliminate the need for the plate securing brads 30.

The arm 12 might be bent, after being so ap-

plied as desired to extend to greater or lesser extent toward a vertical or horizontal position.

For the securement of the bracket to a rail or other member, as in Fig. 4, where the body portion 14 of the attaching plate does not provide clearance for the slot 16, as it does in Fig. 3, the mounting end 20 of the bracket arm would be bent downwardly relative to the arm, for example, as has been indicated in dotted lines 20' in Fig. 3. Then the arm is applied to the slot 16 of the attaching plate, as seen in Fig. 4. In this relationship of parts, the end portion 20 of the bracket arm engages flatly against the front of the support to hold the bracket arm extended for use, and in this application of the device, the arm might also be bent to cause it to assume the desired angle.

If it is desired to apply the bracket to a casing, as at 28 in Fig. 5, the plate 10 may be secured to the casing by nails or screws applied through the holes 15 in flange 13. In this mode of use, the body portion 14 of the plate is horizontally disposed and the bracket arm applied thereto as in Fig. 3, but the end portion 20 of the bracket arm here engages against the underside of plate 14 for the support of the bracket arm in an outwardly and upwardly directed position.

In lieu of forming the plate flange 13 with the holes 15 for securing tacks, or brads, the flange may have teeth as at 40 in Fig. 6, struck downwardly from its rear edge for holding contact with a window rail or part when applied as in Fig. 1.

As an alternative construction, the securing plate might be made as seen in Fig. 7, wherein the lower edge portion of the body portion 14 of the plate is recessed as at 45 and the metal at the lower edge of the plate and at opposite sides of the recess is formed in back turned loops 46, to receive and hold a pin 48 by which the bracket

arm, when applied to the recess, is adapted to be supported. The pin 48 is easily removable for quick detachment or removal of the bracket arm.

Devices of this kind might be made in various sizes and of ornamental metal to add to their attractiveness or ornamental value. They are easy to apply, readily adapt themselves to various uses, and are relatively inexpensive.

Having thus described my invention, what I claim as new therein, and desire to secure by Letters Patent, is:

The combination with a bar having a horizontal top surface and a vertical front surface, of a bracket comprising a mounting plate disposed flatly against the said front surface and formed along its top edge with a flange to flatly engage against the said top surface of the bar, said plate having a horizontal slot in the lower portion thereof, and a bracket arm extended through said slot for pivotal support therein, and bent downwardly at opposite sides of the plate to form a seat, the outer portion of the arm being extended upwardly and outwardly from the plate and formed with an end hook portion for the support of an article therein, and the inner portion of the arm being extended to engage the under side of the bar.
